UNITED STATES PATENT OFFICE.

SHERMAN S. WITTINGTON, OF ADRIAN, MICHIGAN, ASSIGNOR TO ADRIAN WIRE FENCE COMPANY, OF ADRIAN, MICHIGAN, A CORPORATION OF MICHIGAN.

WIRE FENCE.

SPECIFICATION forming part of Letters Patent No. 749,137, dated January 5, 1904.

Application filed June 9, 1902. Renewed May 22, 1903. Serial No. 158,378. (No model.)

To all whom it may concern:

Be it known that I, SHERMAN S. WITTINGTON, a citizen of the United States, residing at Adrian, in the county of Lenawee, State of Michigan, have invented certain new and useful Improvements in Wire Fences; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to wire fences; and it consists in the construction and arrangement of parts hereinafter fully set forth.

The object of the invention is to provide means for locking the horizontal wires to the stay-wires in such manner as to firmly bind said wires together and yet allow a slight vertical or tilting movement of the horizontal wires at their point of contact with the stay-wires, so as to enable the fence to conform to any unevenness in the surface of the ground without kinking the horizontal wires or throwing the stay-wires out of vertical alinement.

The above object is attained by the structure illustrated in the accompanying drawings, in which—

Figure 1 is an elevation of a fence involving my invention. Fig. 2 is an enlarged plan view of the locking-wire uniting the stay-wire to the horizontal wire, the stay-wire appearing in section. Fig. 3 is a perspective view of one of the locking-wires securing the horizontal wire to the stay-wire. Fig. 4 is a perspective view of the locking-wire. Fig. 5 is an elevation of Fig. 3, showing by dotted lines the permitted movement between the horizontal wire and stay-wire.

Referring to the characters of reference, 1 designates the horizontal wires of a fence, which are supported in any desired manner upon the posts 2. The stay-wires 3 are double, being composed of parallel vertical strands or legs united by a loop at the top. The horizontal wires pass between the strands or legs of the stay-wires and are kinked at their points of contact with the strands of the stay-wires, as shown at 4 and 5, to prevent lateral move-

ment between the stay-wires and the longitudinal wires of the fence.

The locking-wire comprises a loop 6, having parallel arms 7. These locking-wires are so placed upon the fence as to embrace the horizontal wire in the loop thereof, while the opposed parallel arms of the locking-wire pass over one strand of the stay-wire and between both strands, their free ends being formed into eyes 8, which embrace one of the strands of the stay-wire upon opposite sides of the horizontal wire, which lies midway between the arms of said locking-wire. By this lock or tie the stay-wire and horizontal wires are so united at their points of crossing as to prevent lateral displacement; but at the same time provision is made to allow a tilting of the horizontal wires between the arms of the lock, as shown by dotted lines in Fig. 5, thereby enabling the fence to be placed upon an incline and at the same time maintain the stay-wires in a vertical position. Because of the fact that the arms of the lock pass between the legs of the stay-wire and have eyes which embrace the stay-wire upon the side crossed by the horizontal wire any tensile strain upon the horizontal wire calculated to draw it into a straight line will not crowd the eyes of the tie open by pressure against the stay-wire for the reason that the bearing will be against the body of the lock and not against the turned ends of the eyes.

Having thus fully set forth my invention, what I claim as new, and desire to secure by Letters Patent, is—

1. In a wire fence, the combination with the horizontal wire having bends therein, of the looped locking-wire engaging with its loop end the horizontal wire, the double stay-wire crossing the horizontal wire vertically with its legs standing on opposite sides of said wire and lying in the bends therein, the locking-wire being in the form of a staple and passing over one and between the two wires of the double stay-wire astride of the horizontal wire, the ends of the locking-wire having eyes which embrace one strand of the vertical stay-wire on the side thereof crossed by the horizontal wire.

2. In a wire fence, the combination of the

horizontal wire, the double vertical stay-wire crossing the horizontal wire, said horizontal wire having a reverse bend, and the wires of the vertical stay standing on opposite sides of the horizontal wire and lying in said bends, the looped locking-wire engaging the horizontal wire at its loop end, and having parallel arms which pass over one of the wires of the vertical stay and extend between the strands thereof parallel to and on each side of the horizontal wire, the free ends of the locking-wire having eyes which embrace one

of the strands of the stay-wire upon the side crossed by the horizontal wire, the arms of said locking-wire standing apart to allow a 15 vertical movement of the horizontal wire between said arms.

In testimony whereof I sign this specification in the presence of two witnesses.

SHERMAN S. WITTINGTON.
